SNAP-ON DRAWER LOCK

William A. Poe, Muskegon, Mich., assignor to Browne-Morse Company, Muskegon, Mich.

Application February 27, 1948, Serial No. 11,710

4 Claims. (Cl. 312—333)

1

This invention relates to drawer locks and more particularly to a drawer lock that is easily and quickly attached to a file cabinet or the like.

In the manufacture of steel filing cabinets and other cabinets or desks with drawers, it is desirable to have as much of the cabinet assembled without tools in bringing about reduced cost of manufacture. It has also been found that some purchasers sometimes buy a cabinet without a drawer lock only to find later that a lock is desirable and applicant has found that an easily installed drawer lock is much to be desired.

The primary purpose of the present invention is to provide a drawer lock for a filing cabinet or the like that is easily and simply installed onto the cabinet either at the factory or in the field to a previously purchased cabinet.

Other purposes and objects of the invention are to provide a drawer lock in which because of the simplicity of manufacture and the ease of installation the cost of both the manufacture and assembly are greatly reduced; differing from the conventional form of construction there are no screws, bolts or nuts to handle and no tools required for the assembly thereof; with the ease and simplicity of assembly, the lock may be installed in the field without tools and without any special skill; the drawer lock parts are stampings being quickly and economically made in a punch press at a greatly reduced cost; when once installed the lock cannot become accidentally removed or dislocated from the cabinet.

Other objects and advantages of the present invention will appear during a reading of the following description taken in connection with the accompanying drawings in which:

Figure 1 is a fragmentary horizontal sectional view through a filing cabinet with a drawer therein showing my improved drawer lock attached thereto.

Figure 2 is a fragmentary elevational view of a portion of the filing cabinet and the drawer supporting channel with the drawer lock attached thereto.

Figure 3 is a vertical sectional view through the side of the filing cabinet and the drawer supporting channel with the drawer lock in elevation, taken along line 3—3 in Figure 2.

Figure 4 is a fragmentary side elevational view of the drawer supporting channel and drawer lock.

Figure 5 is a plan view of the snap on drawer lock unit.

Figure 6 is a perspective view of the drawer lock unit.

lock unit slightly separated from the drawer supporting channel.

Referring to the details of the drawing in which like reference numerals refer to like parts throughout the several views and particularly to Figure 1, a filing cabinet, desk or the like has a side panel 1, a back panel 2 and a front side member 3 bordering a drawer opening 4. The side panel 1 of the cabinet is provided with a rear vertical flanged channel 5 and a forward vertical flanged channel 6 attached thereto as by welding. A horizontally disposed drawer supporting channel 7 is secured at its ends in any convenient manner to the vertical channels 5 and 6. The drawer supporting channel 7 is formed in vertical cross section with a vertical web 8 with narrow horizontal ledges 9 extending horizontally from the upper and lower edges thereof, each with an inwardly vertically extending narrow flange 10.

This drawer supporting channel 7 slidably supports a drawer 11 in the conventional manner whereby the drawer may be withdrawn to extended position out of the front side of the filing cabinet. The drawer is constructed with vertical side members 12, a rear panel 13 and a front panel 14 all assembled together as by welding to form the complete drawer. A stop block 15 is welded or otherwise secured to one side 12 of the drawer 11.

The drawer supporting channel 7 is pierced along two spaced parallel horizontal lines and the metal so cut is bent slightly to the rear of the web of the channel forming the spaced holding strap 16. Slightly below this strap 16 the web of the drawer supporting channel is pierced along an inverted U-shape line and this metal is pressed slightly to the rear of the web of the channel forming the upwardly extending spaced vertical tongue 17.

This strap 16 and the tongue 17 are adapted to support a bracket 18 on which the latch of the drawer lock is mounted. The drawer lock bracket 18 has a vertical leg 19 and an integral horizontal leg 20. The vertical leg is formed with a rectangular notch 21 that is received over the base of the tongue 17 when the lock is properly installed. The vertical leg 18 is pierced along an inverted U-shape line and the metal forced slightly outwardly forming the lip 22 that engages below the strap 16 when the lock bracket is properly in place on the supporting channel and prevents the unintentional removal of the bracket from the channel.

A latching member 23 is made of strap metal

and is pivotally mounted on the horizontal portion 20 of the bracket 18 on the pivot pin 24. A stop lug 25 is formed from the metal of the latching member 23 and extends downwardly therefrom and engages one edge of the horizontal leg of the bracket to stop the counter clockwise rotation of the latching member on the bracket. The pivot pin 24 extends a distance above the latching member and a torsion spring 26 is located around this pivot pin with one end 27 thereof hooked over the rear edge of the latching member 23 and the other end 28 of the torsion spring engaging one edge of the vertical leg of the bracket 18 yieldably rotating the latching member counter clockwise and with the stop lug 25, against this bracket.

A lock operating strap 29 is located vertically along the rear side of the vertical cabinet channel 6 and is actuated by motion of a key operated drawer lock and when actuated is rotated slightly thus moving the stop lug end of the latching member inwardly and removing the other end of the latching member from the path of the drawer stop block 15 whereby the drawer may be slid outwardly to open position.

With the parts made as described the drawer lock may be easily assembled onto the drawer supporting channel. To assemble the drawer lock to the drawer supporting channel the vertical leg 19 of the bracket 18 is inserted downwardly between the rear face of the web 8 of the drawer supporting channel 7 and the strap 16 until the lip 22 binds against the strap. Then with a heavy instrument or object the bracket is forced or hammered further downward until the lip 22 snaps outwardly adjacent the lower edge of the strap 16 and until the rectangular notch 21 straddles the tongue 17. Thus the upper portion of the bracket is held snugly between the strap and the rear face of the supporting channel, the lip 22 engaging the lower edge of the strap 16 prevents unintentional removal of the bracket from the supporting channel and the lower end of the bracket 18 is held from longitudinal movement by the notch in the end thereof straddling the tongue 17 and is held from lateral movement by the tongue 17 holding the lower end of the bracket against the rear side of the supporting channel.

Having thus described my invention it is understood that I have devised a drawer lock that is easily installed either at the factory or in the field and that no tools are required for the installation and that I have designed a drawer lock that is economical to manufacture and simple to assemble with the resultant decrease in the manufacturing costs.

Although I have described but one form of structure it is considered that certain minor changes may be made without departing from the spirit and intent of my invention, the entire scope of which is defined in the following claims.

1. A drawer lock comprising a bracket having a vertical leg, the lower end thereof terminating in a bifurcated portion, a latching member pivoted on said bracket, a vertical drawer supporting member having a horizontal strap attached at its ends to the supporting member and spaced from the one face of the supporting member, and also having an upwardly extending tongue attached thereto and spaced from the same face thereof, the bracket receivable between the strap

and the rear face of the supporting member and the lower terminal end thereof receivable between the tongue and the rear face of the supporting member and the bifurcated portion receivable astraddle the tongue.

2. A drawer lock comprising a bracket made of strap metal and having a horizontal leg to which is pivotally attached a latching member and having a vertical leg terminating at its lower end in a bifurcated portion, a vertically disposed drawer supporting member of sheet metal having a horizontal strap pierced therefrom and spaced from the face thereof, an upwardly extending tongue pierced from the supporting member below the strap and spaced from the face of the supporting member, the vertical leg of the bracket receivable between the strap and the face of the supporting member and the lower end of the bracket receivable between the tongue and the face of the supporting member with the bifurcated portion thereof straddling the base of the tongue.

3. A drawer lock comprising a bracket having a vertical leg, said leg of the bracket having an outwardly and upwardly extending lip and terminating at its lower end in a bifurcated portion; a latching member pivoted to said bracket, a vertical drawer supporting member having a horizontal strap attached at its ends to the supporting member spaced from a face thereof, the supporting member also having an upwardly extending tongue attached thereto below the strap and spaced from said face thereof, the vertical leg of the bracket receivable between the strap and said face of the supporting member with the lip snapped outwardly below the strap and the lower end of the vertical leg of the bracket receivable between the tongue and the rear face of the supporting member with the bifurcated end of the bracket straddling the base of the tongue:

4. A drawer lock comprising a vertically positioned drawer supporting member of sheet metal having a strap pierced therefrom and bent in spaced relation to one face thereof, an upwardly extending tongue pierced from the supporting member below the strap and bent to spaced relation to the same face of the supporting member, a bracket having a horizontal leg to which is pivotally attached a latching member and also having a vertical leg with an upwardly and outwardly extending lip and at its lower terminal end provided with a central notch, the vertical leg of the bracket receivable between the strap and the face of the supporting member with the lip located outwardly below the strap, the lower end of the bracket receivable between the tongue and the face of the supporting member with the notch end of the bracket straddling the base of the tongue.
